F. W. ERICKSON,
COMBINED ELECTRIC SWITCH AND ELECTRIC FUSE,
APPLICATION FILED SEPT. 11, 1920.

1,414,011.

Patented Apr. 25, 1922.

UNITED STATES PATENT OFFICE.

FREDERIC WM. ERICKSON, OF NEW YORK, N. Y.

COMBINED ELECTRIC SWITCH AND ELECTRIC FUSE.

1,414,011.

Specification of Letters Patent. Patented Apr. 25, 1922.

Application filed September 11, 1920. Serial No. 409,586.

To all whom it may concern:

Be it known that I, FREDERIC WM. ERICKSON, residing at New York, in the county of New York and State of New York, have invented certain Improvements in Combined Electric Switches and Electric Fuses, of which the following is a specification.

This invention relates to electric switches employed in high tension circuits such as electric power and light circuits, and refers particularly to such switches having a fusible member forming a part of the switch.

The principal object of the invention is to provide an improved switch of this character which can be quickly and safely re-fused. To this end the device includes a switch arm having, as a part thereof, a fuse preferably of the standard type, the parts being so mounted and connected that a compound motion consisting of a swing of the arm and then a pull will entirely disconnect the arm to enable a fresh fuse to be substituted for a blown one.

Further objects of the invention are to provide a combined switch and fuse so constructed that when it is to be re-fused the member which is to receive the fresh fuse will remain in a safe predetermined position, and to provide such a device which can be economically manufactured.

With the above objects in view the invention consists in the construction and combination of parts substantially as herein-after described and claimed.

35 In the drawing forming a part of this specification,

Figure 1 is a side view of the combined fuse and switch attached to an insulating support or back, dotted lines indicating the position of the switch arm when thrown and ready for a fresh fuse to be substituted for a blown one.

Figure 2 is a perspective view of a standard electric fuse.

45 Figures 3 and 4 are sectional views of the parts which hold the upper end of the fuse and form the upper part of the switch arm.

Figure 5 is a perspective view of the same, omitting the handle.

50 Figure 6 is an elevation of some of the parts shown in Figure 1 looking from the left of that figure and showing the side leaves of the upper grip or jaw in section.

55 Figures 7, 8 and 9 are, respectively, front, top, and side views of the trunnioned socket for the lower end of the standard fuse.

Similar reference characters indicate similar parts in all of the views.

An intermediate part of the switch arm consists solely of the fuse which, as illustrated, is preferably of the standard type having an insulating cylinder or shell 1 provided with metal caps or terminals 2, 3, the fuse strip or wire being indicated in Figure 2 at 4.

60 Secured to a suitable base by screws 17 are a lower jaw or equivalent support 12 for the trunnioned socket 14, and an upper jaw 13. Binding plates for the circuit wires are indicated at 16, said plates being secured by 65 screws 18.

The socket 14 is formed with resilient sides as by providing cuts 15 therein, and it is formed with trunnions 20 mounted in holes 19 in the sides of the lower jaw 12. It 70 is also provided with ridges or ribs 25 the purpose of which will be presently explained.

The diameter of the socket 14 is such as to receive one end cap of the fuse snugly, preferably with a friction fit. To firmly grip or clamp the other end of the fuse and coact therewith and with the socket 14 in forming a switch arm, I provide a divided housing consisting of semi-tubular grip members 9, 80 10, having inwardly bent lips 11 at their lower edges and having tapering upper portions terminating in straight tips or fingers which are firmly embedded at 6 in a handle 5 of suitable insulating material. The connection with the handle is such that the members 9, 10, tend to open or spring apart as indicated in Figure 4 when permitted to do so. Within the handle and surrounding the upper portions of the members 9, 10, is an 85 internally threaded thimble 7. A nut 8 also surrounds the upper portions of the members 9, 10, and has a milled portion to be grasped by the user's fingers and an externally threaded portion engaging the internal threads of the thimble 7.

90 By operating the nut toward the position indicated in Figures 3 and 6 the members 9 and 10 can be closed so tightly over one of the end caps of the fuse as to firmly grip it and hold the 95 fuse rigidly. Therefore, when the parts are assembled as in Figure 1, the pivoted or trunnion socket and the fuse and the clamp with its handle constitute a single switch arm of which the fuse forms the intermediate part. 100 When the said arm occupies the position shown by the full lines in Figure 1, a cir-

cuit is completed through the jaws 12, 13, which circuit is broken by throwing the switch open to a position such as indicated by the dotted lines in that figure.

- 5 If the fuse has blown, the user will continue the outward swinging movement so as to exert a pull to remove the lower end of the fuse (or its lower cap) from the socket, such movement as a whole being a compound 10 one which enables the user to very quickly shift the fuse and its clamped handle to a position removed from the jaws preparatory to operating the screw or nut 8 to release the blown fuse.
- 15 When a fresh fuse has been gripped by the housing 9, 10, all that is necessary to restore the parts to operative condition is to push the lower end of the fuse into the socket and swing the arm back to the position shown by full lines in Figure 1. To facilitate such re-assembling of the parts, I provide for holding the socket in a predetermined tilted or angular or inclined position ready for the insertion of the lower end 20 of the fuse thereinto. To this end the inner faces of the jaw members 12 have inclined grooves 22 which may be formed by the die employed when the said members are struck up from sheet metal. When the switch arm 25 is swung out, the ribs or ridges 25 of the socket interlock with the grooves 22 of the lower jaw members. If the outward swing is effected only for the purpose of breaking the circuit, the interlocking described serves 30 to hold the switch arm in position such as indicated by the dotted lines in Figure 1. If the fuse is then pulled out of the socket 14, said socket remains in a convenient predetermined position for the insertion thereinto 35 of a fresh fuse end.

I do not limit myself to the employment of jaw members 12 and 13 as the circuit terminals which are to be joined or bridged by the switch arm, as any mechanical equivalents which will serve the purpose of pivotally supporting the socket and of holding the upper end of the arm in circuit-closing position may be substituted for jaws without departing from the spirit and scope of 45 my invention.

Having now described my invention, I claim:

1. In a device of the character described, a switch arm comprising a socket, a fuse hav-

ing a friction fit therein, and a handle detachably connected with the other end of the fuse.

2. A combined electric switch and fuse having a switch arm comprising a socket, a fuse having a friction fit therein, and a handle detachably connected with the other end of the fuse, means for pivotally supporting the socket, and means for holding the socket in predetermined inclined position when the arm is in circuit-breaking position.

3. A combined electric switch and fuse comprising a pair of circuit terminals, a fuse having a metal ferrule at each end, means for separably and pivotally connecting one ferrule with one of said terminals, a clamp embracing the other ferrule, and a handle connected with said clamp, said clamp being in position to coat with the other terminal to close a circuit.

4. A combined electric switch and fuse comprising a pivoted socket, a fuse member having metal terminals one of which removably fits said socket, an insulated handle having a separable clamp connection with the other terminal of the fuse, and means for engaging said clamp connection to hold the fuse in circuit closing position.

5. A combined electric switch and fuse comprising a pivoted support, a jaw in alignment therewith and insulated therefrom, and a fuse having metal terminals removably connected at one end with said pivoted support and having a handle directly connected with its other end to enable the fuse to be swung to or from the jaw to complete or break a circuit.

6. A switch-mounting for a fuse, comprising a pivoted socket for one end of the fuse, means for holding the other end of the fuse in position to close a circuit, and means coacting with the circuit to hold it and the fuse in predetermined circuit breaking position.

In testimony whereof, I have signed my name to this specification in the presence of two subscribing witnesses, this eighth day of September, 1920.

FREDERIC WM. ERICKSON.
